UNITED STATES PATENT OFFICE

ROY V. YEAGER, OF DES MOINES, IOWA

STRUCTURAL FLOOR

Application filed March 13, 1928. Serial No. 261,209.

My invention relates to that class of structural floors in which there is employed a series of structural joists provided with shoulders at their sides upon which plaster board 5 may be laid between the joists, to temporarily support the concrete floor above the plaster board and the joists until the same has set and hardened and become bonded with the plaster board.

10 The object of my invention is to provide a structure of this character which may be readily and quickly produced by the use of inexpensive materials that can be obtained in almost any locality, and in which the 15 strains upon the plaster board, which might tend to cause them to break or bend during the process of construction, are minimized; and also to provide a reinforcement for the plaster board which will quickly set and 20 harden and form a strong and durable support to receive the concrete floor; and also to provide a structure of this character in which a minimum of concrete is employed for the floor and yet the finished floor will have 25 the same strength as though a greater amount of concrete were used.

My invention consists in the construction of the floor, whereby the objects contemplated are attained, as hereinafter more fully set 30 forth, pointed out in my claim, and illustrated in the accompanying drawings, in which:

Figure 1 shows a vertical sectional view through a portion of a floor embodying my invention; and

35 Figure 2 shows a vertical sectional view of same on the line 2—2 of Figure 1.

Referring to the accompanying drawings, I have used the reference numeral 10 to indicate a structural joist. Formed on the sides 40 of this joist, between the upper and lower chords thereof, are shoulders at 11. These may be formed in various ways, but as illustrated herein they are formed by a body of gypsum 12 moulded around the body portion 45 of the joist with the top surface thereof flat to form these shoulders.

When two adjacent joists are placed, then the operator places a sheet of plaster board 50 13 between the joists with the edges of the plaster board resting upon the shoulders 11.

Then the operator places a quantity of plastic gypsum upon the plaster boards and surfaces it off, so that it will be relatively thick in the center and tapering toward the ends of the plaster board, as shown at 14 in Figure 1. 55

Before the gypsum 14 is applied, a series of reinforcing rods 15 is placed upon the top chords of the joist and permitted to sag downwardly above the central portions of the plaster boards 13, as shown in Figure 1; and also 60 longitudinally extending rods 16 are provided and placed upon the tops of the rods 15.

This plastic gypsum has the quality of quickly setting and hardening, and since a relatively small quantity of it is used, and it 65 is of lighter weight per cubic foot than concrete, it is obvious that no great strains are applied to the plaster boards during the time the gypsum is being applied. Then when the gypsum sets and hardens, which takes place 70 in a few minutes, a temporary floor has been provided which has a considerable degree of strength, because the gypsum is braced by the reinforcing rods and the gypsum becomes bonded to the plaster board. 75

As soon as the gypsum has become set and hardened, the concrete floor may be laid, and this is done in the ordinary manner, and the temporary floor formed by the plaster board and gypsum is sufficiently strong to permit 80 the workmen to walk about upon the temporary floor while the concrete is being poured or surfaced. The concrete floor then becomes bonded with the gypsum and is reinforced by the reinforcing rods in the ordinary manner. 85

The completed floor is of substantially the same thickness as ordinary reinforced concrete floors, but it is less weight on account of the presence of the lighter material, gypsum. However, it has substantially the same 90 strength, because the floor from one joist to another is of the arched structure commonly employed in bridges and culverts.

By the term "plaster board" as used herein, I refer to the ordinary building boards of various types and materials now in common use, whether actually embodying in their construction a plaster or not; and by the term "gypsum" as herein employed, I do 100

not desire to be understood as limiting myself to the so-called pure gypsum, but refer to a quick setting plastic composition of any character.

5 I claim as my invention:

An improved floor construction, comprising a series of joists spaced apart, plaster boards supported by the joists between the upper and lower ends thereof and covering the spaces between two joists, reinforcing rods resting upon the tops of the joists and sagging downwardly to position adjacent to the plaster boards at the central portion of the space between two joists, a layer of gypsum placed upon the plaster boards and tapered from a maximum thickness at the center between two joists to a minimum thickness adjacent to the joists, and surrounding said reinforcing rods, and a top layer of cement completely enclosing the upper ends of the joists and the reinforcing rods supported thereby and forming an arch shaped reinforced concrete slab between the joists, substantially as and for the purposes stated.

25 Des Moines, Iowa, March 5, 1928.
ROY V. YEAGER.
